UNITED STATES PATENT OFFICE.

IRA W. SIPES, OF WILMETTE, ILLINOIS.

STORM-SASH BRACKET.

1,306,929.

Specification of Letters Patent. Patented June 17, 1919.

Application filed February 23, 1918. Serial No. 218,819.

To all whom it may concern:

Be it known that I, IRA W. SIPES, a citizen of the United States, residing at Wilmette, in the county of Cook and State of Illinois, have invented a new and useful Storm-Sash Bracket, of which the following is a specification.

The subject of the present invention is a storm sash bracket which is designed to support a hingedly hung storm sash in opened or closed positions.

The invention contemplates the provision of means for locking the bracket to hold the sash when closed.

15 A further object within the contemplation of the invention is the provision of means for supporting the arms when in extended position to hold the sash opened.

20 The invention also contemplates the production of a simple, durable and efficient storm sash bracket.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 25 within the scope of what is claimed without departing from the spirit of the invention.

A practical embodiment of the invention is illustrated in the accompanying drawing, wherein:—

35 Figure 1 is a view in side elevation of the device, a fragment of the sash and sill to which it is attached being shown, the sill in section, the device shown in extended position in dotted lines;

40 Fig. 2 is a plan view of the device in extended position;

Fig. 3 is a plan view of the latch or lock, the bracket arms shown in section;

45 Fig. 4 is a view in elevation of the sill attaching bracket, the connecting pin shown in section.

Referring to the drawing by numerals of reference:—

The outer sill of a window is indicated at 50 1, and a fragment of a storm sash is seen at 2.

In carrying out the invention an attaching or supporting bracket 3 is secured by screws or otherwise to the upper surface of the outer sill 1 at that portion of the sill lying 55 between the regular sash (not shown) and

the storm sash 2. The upstanding end of the bracket 3 is provided with a recess 4 which has a narrow entrance or mouth leading to an enlarged head of circular formation. A flattened headed pin 5 is adapted to enter the recess 4 in which it is locked except in one position of the pin, as will be readily understood.

60 The pin 5 is riveted or otherwise secured to one end of a supporting arm 6 from which it extends laterally. The other end of the arm 6 merges into an attenuated portion having an angled or laterally extending finger 7 which is adapted to overlie an arm 70 8 when the bracket is in extended position and support the arms.

75 The arm 8 is pivotally secured to the arm 6 and has riveted or otherwise secured thereto a metal strip 9 which is slightly resilient and offset at one portion to form a latch adapted to snap past the arm 6 when the storm sash is closed and so lock the arms together.

80 Pivottally attached to the other end of the arm 8 is an angled attaching bracket 10 which is secured by screws or otherwise to the sash 2.

85 From the foregoing it will be understood that when it is desired to open the storm sash, the latch 9 is released from the arm 6 and the sash pushed outwardly until the arms 6 and 8 are in extended position, at which time the finger 7 will come into contact with the upper edge of the arm 8 and 90 prevent the arms from pivoting beyond the position of extension. The arms will then serve to hold the sash opened.

95 When the sash 2 is removed in the summer time the pin 5 is readily and easily withdrawn from the recess 4 and the sash removed without the necessity of unscrewing the parts.

Having thus described the invention, what is claimed as new and sought by Letters Patent, is:—

In a device of the class described, a pair of arms having their inner ends connected; means for pivoting the outer ends of the arms, respectively, to a frame and to a sash; 105 and a spring strip having one of its ends secured to the outer surface of one arm and extended in hook-shape across the edge of said arm and along the opposite surface of said arm in spaced relation thereto to provide 110 for the reception of the other arm when the arms are folded into alinement, the strip

being provided with a lateral shoulder co-operating with the said other arm and terminating in a guiding finger adapted to receive the said other arm and to direct the same into coöperating relation with respect to the seat.

In testimony that I claim the foregoing

as my own, I have hereto affixed my signature in the presence of two witnesses.

IRA W. SIPES.
